FIG. 1.

FIG. 2.

INVENTOR

David J. Rosenberg

UNITED STATES PATENT OFFICE

106,379

DESIGN FOR A SUIT

David J. Rosenberg, New York, N. Y.

Application August 18, 1937, Serial No. 71,160

Term of patent 3½ years

To all whom it may concern:

Be it known that I, David J. Rosenberg, a citizen of the United States of America, residing in New York city, in the Borough of Manhattan, county and State of New York, have invented a new, original, and ornamental Design for a Suit, of which the following is a specification, reference being had to the accompanying drawing, forming part thereof, wherein,

The dotted area on the jacket portion of the suit represents a fur fabric.

I claim:

The ornamental design for a suit, substantially as shown and described.

DAVID J. ROSENBERG.
